SHUTTLE BOX AND SHUTTLE FOR FILLING
REPLENISHING LOOMSJames M. Jenkins, Kannapolis, N. C., assignor of
one-half to Claude O. Plott, Concord, N. C.

Application March 1, 1950, Serial No. 147,081

2 Claims. (Cl. 139—183)

1

This invention relates to an improvement in shuttle boxes for filling replenishing looms and more especially to an improved shuttle box front and an improved shuttle, the shuttle box front and the shuttle having cooperating elements thereon for retaining outgoing weft yarn from the shuttle in a desired position to insure proper engagement thereof by the conventional type of yarn clamp and cutter mechanism during a bobbin transfer operation.

This invention is adapted to be associated with a filling clamping and cutting mechanism of a type such as is shown in the patent to A. E. Stafford, No. 1,552,388 of September 1, 1925, but is not restricted to use with this particular type of clamping and cutting apparatus.

It is well known to those familiar with the art, that shuttles used with looms of the filling replenishing type are provided with an opening at one side thereof which coincides with an opening of similar dimensions in the usual type of shuttle box front when the shuttle is in the shuttle box. Upon a filling replenishing operation taking place, the usual type of clamping and cutting device moves into an operative position, that is, the device enters the coinciding openings in the shuttle and shuttle box front and simultaneously grasps the outgoing yarn, which extends from the shuttle to the adjacent selvage of the cloth, as it passes the opening in the shuttle to hold one portion of the yarn while severing another portion thereof to permit the spent bobbin to be discharged from the shuttle as a filled bobbin replaces the same.

It is also well known that the shuttle, upon being boxed, will usually rebound prior to its being again thrown out of the shuttle box. It is evident that this rebounding of the shuttle will cause the weft yarn to sag between the shuttle eye and the adjacent selvage of the fabric being woven with the result that, upon the transfer operation taking place, the weft yarn will, at times, be disposed at a lower elevation than the clamping and cutting mechanism as it enters the coinciding openings in the shuttle and the shuttle box front.

It is therefore an object of this invention to provide cooperating means on the shuttle box front and the proximate surface of the shuttle when the shuttle is boxed, which will insure that the outgoing weft yarn from the shuttle eye will not only remain taut but will also retain its desired elevation across the openings in the shuttle and the shuttle box front.

It is another object of this invention to provide,

in a loom having a shuttle box, a shuttle box front adapted to be secured to the shuttle box and a shuttle adapted to be received and discharged from the shuttle box, the shuttle box front and the shuttle having coinciding openings therein past which the outgoing weft yarn from the shuttle is adapted to be disposed upon the shuttle being boxed, said shuttle having a smooth imperforate area between its shuttle eye and the opening, the opening being adapted to accommodate the usual type of filling clamping and cutting apparatus. The box front is provided with a leaf spring member adapted to frictionally engage the yarn upon the shuttle being boxed and to hold the yarn against the imperforate area to thus support the yarn adjacent one side of the coinciding openings in the shuttle and the shuttle box front, and the leaf spring member also serving to retain tautness of the yarn upon the shuttle rebounding following its being boxed and causing the loose portion of the weft yarn resulting from the rebounding of the shuttle to be disposed between the shuttle eye and the opening which is adapted to receive the clamping and cutting apparatus to insure proper engagement with the weft yarn by the clamping and cutting apparatus.

Some of the objects of the invention having been stated, other objects will appear as the description proceeds when taken in connection with the accompanying drawings in which—

30 Figure 1 is a top plan view of a shuttle box showing a shuttle therein;

Figure 2 is a fragmentary elevation of the shuttle box and shuttle shown in Figure 1;

35 Figure 3 is an enlarged sectional plan view of the shuttle and the box front with parts broken away taken substantially along the line 3—3 in Figure 2 but omitting other parts of the shuttle box;

40 Figure 4 is an isometric view showing the top, front and inner end of the improved shuttle;

Figure 5 is an enlarged isometric view of the shuttle box front shown in Figures 1, 2 and 3 and looking at the inner and upper surfaces and the outer end thereof and showing the improved leaf spring member associated therewith for engaging the smooth surface on the improved shuttle shown in Figure 4;

50 Figure 6 is an enlarged vertical sectional view through the lay and shuttle box shown in Figure 2 and being taken substantially along the line 6—6 in Figure 2 and also showing a portion of a filling replenishing mechanism and a clamping and cutting mechanism associated therewith, this clamp-

ing and cutting mechanism being of a type substantially as shown in said Patent No. 1,552,388.

Referring more specifically to the drawings, the numeral 10 indicates the lay of a loom which is oscillated in the usual manner and which has associated therewith a reed cap 11. A lay end 12 of a shuttle box broadly designated at 13 is secured on the right-hand end of the lay 10, in Figures 1 and 2, in the usual manner. A back box plate 14 and a binder 15 are secured to the lay end 12 by a bolt 16. The lay end 12 has a slot 17 therein in which a conventional picker stick 20 has longitudinal sliding movement and on which a picker 21 is mounted, the picker 21 being adapted to engage and throw a shuttle broadly designated at 22 out of the shuttle box 13 and across the lay 10. An improved shuttle box front 23 is secured to the upper surface of the lay end 12, as by screws 24.

There are many types of shuttle boxes and box fronts which may be used in association with the present invention and, although the shuttle box 13 shown in Figures 1 and 2 is of the type such as is employed in association with a filling replenishing loom, the shuttle box 13, the shuttle 22 and the shuttle box 23 should not be restricted to a type employed in a filling replenishing loom since the features of this invention may be employed in association with pick and pick box looms or shuttle changing looms or any other type of loom wherein a shuttle is employed and is projected across the lay of the loom to be received by shuttle boxes at opposed ends thereof.

However, this invention does relate to the particular feature of the shuttle 22 in combination with the box front 23 which includes means for holding the outgoing weft yarn from the shuttle 22 taut so as to cause the yarn to remain in an elevated position as it passes the usual opening provided in shuttle box fronts of the type adapted to be associated with filling replenishing looms so the thread clamp and cutter apparatus may engage this portion of the outgoing weft yarn. The shuttle in Figures 1, 2 and 4 has a bobbin or quill 25 therein from which weft yarn 26 is drawn through the usual shuttle eye and this shuttle as well as the shuttle box front 23 will be later described in detail.

Now, since the shuttle and the box front 23 are adapted to be associated with the filling replenishing type of loom there is shown in Figure 6 a fragmentary elevation of a portion of the usual type of bobbin transfer mechanism and the clamp and cutter mechanism, this clamping and cutting mechanism being clearly shown and described in said Patent No. 1,552,388. The transfer mechanism shown in Figure 6 includes the usual hopper or magazine 30 for holding a series of filling carriers or quills 31, these quills being identical to the quill 25 shown in the shuttle 22. The hopper shown is of the rotary type but the invention is not restricted thereto as any form of filling supply hopper may be employed, the rotary type being shown merely for the convenience of illustration.

The hopper 30 is mounted on the usual hopper stand 32 which has a transerrer shaft 33 extending therefrom on which is oscillatably mounted a transfer arm 34 for transferring a bobbin or quill 31 from the hopper 30 to the shuttle 22 in the usual manner.

Integral with the transfer arm 34 is an arm 35 which extends downwardly therefrom, in Figure 6, and has a dog 36 pivotally connected thereto, as at 37, and the free end of which is adapted

to be engaged by a bunter on the lay 10 in the usual manner when filling replenishing is caused.

Disposed below the transfer arm 34, in Figure 6, is the usual type of thread clamp and cutter, the nose of which is indicated at 40 and which includes means, as is clearly shown in said Patent No. 1,552,388, for clamping and cutting the outgoing weft yarn 26 extending from the shuttle 22. It is well known that this clamp and cutter mechanism is mounted in such a manner as to be operable simultaneously with movement of the transfer arm 34 during a transfer operation so as to enter the openings provided therefor, to be presently described, in the shuttle box front 23 and in the shuttle 22 to thus clamp and cut the yarn from the ejected bobbin upon the new bobbin or quill being inserted in the shuttle 22 in the usual manner. Of course, the clamping and cutting mechanism indicated at 40 is also automatically operable in the usual manner to move out of operating position during the interim between quill transfer operations.

The shuttle 22 is of the usual well known construction and is of the type having a body portion 45 which is usually of wood construction and which is provided with metallic pointed end portions 46 and 47 suitably secured thereto. The body portion of the shuttle 22 has the usual slot 48 therein into which the filled bobbin 25 is adapted to be projected upon a transfer operation and through which the preceding or spent bobbin is projected upon being discharged in the usual manner when the transfer operation takes place as shown in Figure 6.

The shuttle also includes the usual type of spring loaded clamp members 52 and 53 which clampingly engage the head of the bobbin 25 to hold it in the desired position in the shuttle 22. The shuttle has a conventional metallic shuttle eye member 55 therein of the usual construction and which is secured therein by a bolt 56 extending transversely through the body 45 of the shuttle 22. The shuttle 22 has a shuttle eye opening 57 (Figures 3 and 4) through which the weft yarn 26 is adapted to be pulled with movement of the shuttle 22 across the lay as the yarn is unwound from the bobbin 25 and as it passes through the shuttle eye member 55.

The body 45 of the shuttle 22 is also provided with the usual thread groove 60 which extends substantially the entire length of the shuttle 22 but which does not extend all the way to the shuttle eye opening 57 as has heretofore been the case, the fact that this groove 60 does not extend the full length of the shuttle 22 being one of the features of the present invention.

Now, if so desired, the shuttle eye member 55 may be secured in the shuttle 22 by means other than the bolt 56. However, since this is the usual manner in which the shuttle eye member 55 is secured in the shuttle 22, the shuttle is counterbored, as at 61 so the head of the bolt 57 will be disposed a substantial distance inwardly of the outer surface of the body portion 45 of the shuttle 22 and this counterbore 61 is then filled with a suitable filling material 62 such as plastic, wood filler, or any other desired material. The shuttle 22 is also provided with the usual thread clamp and cutter opening 63, and the outer surface of the body 45 of the shuttle 22 between the opening 63 and the shuttle eye opening 57 is sanded smooth so as to provide a smooth surface, indicated generally at 64, past which the outgoing weft yarn 26 will extend as the shuttle

moves from left to right in Figures 1, 2 and 3 upon being boxed in the shuttle box 13.

The body 45 of the shuttle 22 also has a cavity 70 therein adjacent the clamping and cutting opening 63 but disposed to that side of the opening 63 remote from the shuttle eye opening 57, this cavity 70 preferably being of greater depth than the groove 60.

The bottom of the cavity 70 adjacent the opening 63 has a pin 71 secured therein, as by a pressed fit, and this pin 71 may be a projection from the bottom from the cavity 70 if so desired. The pin 71 projects outwardly to where its outer end is coincident with the outer means surface of the shuttle body 45. It will be observed in Figure 3 that this pin or projection 71 will assist in supporting the outgoing weft yarn 26 adjacent the opening 63 in the shuttle 22.

Now, it is well known that, upon the shuttle being thrown into the shuttle box 13, it engages and moves the picker 21 along with the picker stick 20 outwardly to adjacent the right-hand end of the shuttle box 13 and will, in most instances, rebound immediately upon the picker stick 20 reaching the end of its outward movement. In order to prevent the outgoing weft yarn 26 from kinking and also to assist in holding that portion of the outgoing yarn 26, between the shuttle eye opening 57 and the adjacent selvage of the fabric being woven, taut so as to extend across the shuttle opening 63, I have provided improvements in the shuttle box front 23 to be presently described.

The shuttle box front shown in Figures 1, 2, 3 and 5 may be of any usual construction adapted to be associated with a filling replenishing loom with the exception of the features of the present invention which will be later described. In the present instance, the box front comprises an outer end portion 75 provided with a suitable opening 76 therethrough for reception of the thread clamp and cutter mechanism shown in said patent and also appearing in Figure 6 of the present drawings and the opening 63 in the shuttle 22 coincides with this opening 76 when the shuttle 26 is boxed as shown in Figures 1, 2 and 3. The shuttle box front 23 also has a longitudinally extending and upwardly and inwardly curving slot 77 therein which curves upwardly to the upper surface of the shuttle box front 23 to form an inner end portion 80 as well as upper and lower longitudinally extending portions 81 and 82. The portions 82 and 80 have a longitudinally extending thread groove 82a therein through which the yarn extends from the boxed shuttle 22 to the fabric, not shown.

If so desired, the shuttle box front 23 may have a suitable liner 83, of leather or similar material suitably secured to the inner surface of the inner end portion 80 thereof to absorb the shock of the shuttle 22 as it enters the shuttle box 13.

This particular shuttle box front 23 is also shown as being provided with the usual projections 85 and 86 which are generally termed as thread catchers, and which are conveniently provided for engaging the new filling as the lay 10 moves forwardly at the first pick movement following a bobbin transfer operation.

The structure of the shuttle box front 23 heretofore described is that of the typical shuttle box front and it is with this type of shuttle box front that part of the present invention is adapted to be associated.

The outer end portion 75 (Figures 3 and 5) of

the shuttle box front 23 has an elongated cavity 90 on the inner surface thereof which extends in substantially the same horizontal plane as the said groove 82a on the inner surface of the shuttle box front 23. A resilient thread clamp in the form of a relatively thin leaf spring member 91 is secured in the cavity 90 by any suitable means such as screws 92 (Figure 3). Since the cavity 90 communicates with the opening 76 in the outer end portion 75 of the shuttle box front 23, the leaf spring member 91 is bent or curved forwardly, as at 94, this forwardly curved portion 94 extending partially into the opening 76 in the shuttle box front 23 so as to permit the leaf spring member 91 to be flexed forwardly when desired against the bottom surface of the cavity 90.

It will be observed, in Figure 3, that the cavity 90 and the leaf spring member 91 coincide with the outer end of the shuttle 22 when it is in boxed position as shown in Figures 1 and 3 and the inwardly bent portion or free end of the leaf spring member 91 bears against the smooth surface 64 (Figure 4) of the shuttle body 45. Therefore, upon the shuttle being boxed in the shuttle box 13, the outgoing yarn 26 will be supported by the pin 71 and will be frictionally engaged by the leaf spring member 91 clamping the same against the smooth surface 64 of the shuttle.

Thus, upon the shuttle rebounding following a boxing operation, the yarn will be held against the flat surface of the shuttle body 45 closely adjacent the opening 63 in the shuttle 22 and the yarn will then slacken, as at 95, between the shuttle opening 63 and the shuttle eye opening 57 to thus prevent the yarn 26 from becoming kinked throughout its length between the shuttle eye opening 57 and the selvage of the fabric not shown. This will also insure that the yarn 26 will extend across the openings 63 and 76 in the shuttle 22 and the shuttle box front 23, respectively, so the clamp and cutter nose 40 (Figure 6), moving into operative position through the openings 76 and 63, will properly engage the yarn 26.

It might be stated that the tension of the leaf spring clamping member 91 is relatively light and is not of sufficient strength to exert such a pressure on the yarn 26 as to part the same as the shuttle is boxed and will also permit the shuttle and its yarn 26 to leave the shuttle box 13 without severing the yarn 26.

In the drawings and specification there has been set forth a preferred embodiment of the invention and although specific terms are employed they are used in a generic and descriptive sense only and not for purposes of limitation, the scope of the invention being defined in the claims.

I claim:

1. An improved shuttle and shuttle box front combination for looms, said loom being provided with a lay and also having a shuttle box on at least one end of said lay and being provided with a picker stick having a picker thereon adapted to be engaged by the shuttle as the shuttle is thrown into the shuttle box and also to throw the shuttle out of the shuttle box across the lay, said shuttle having a quill having weft yarn thereon, said shuttle having an eye through which the yarn passes said loom also having an automatically operable yarn clamping and cutting apparatus thereon, said shuttle and shuttle box front being provided with openings which coincide with each other when the shuttle is

boxed in the shuttle box and through which the yarn clamping and cutting apparatus is adapted to extend during a transfer operation, said shuttle having a smooth flat surface on its side adjacent the shuttle box front and disposed between the eye of the shuttle and the opening in the side of the shuttle, said improvement comprising a leaf spring member secured to the shuttle box front and the free end of the leaf spring member being adapted to engage the smooth flat surface on the shuttle when the shuttle is boxed, a projection on said shuttle disposed on the opposite side of the opening from which the flat surface is disposed and whereby, upon the shuttle rebounding following a boxing operation, the weft yarn extending from the shuttle will be supported by the projection at one side of the opening and by the leaf spring member pressing the yarn against the flat surface of the shuttle at the other side of the opening to properly position the yarn for engagement by the yarn clamping and cutting apparatus.

2. An improvement in a loom having a lay and being provided with a shuttle box having a shuttle box front at least one end of said lay and said loom also having a yarn clamping and cutting apparatus, and having a shuttle adapted to be boxed in the shuttle box, said shuttle and said shuttle box front having openings therein which coincide with each other when the shuttle is in boxed position, said shuttle

5 having a shuttle eye therein through which a weft yarn is adapted to pass, the improvement comprising said shuttle eye being in the same horizontal plane as the opening in the shuttle and being spaced therefrom, said shuttle having a longitudinally extending cavity therein having one end thereof in communication with said opening in the shuttle, said cavity having a projection therein adapted to support the weft yarn extending from the shuttle eye, and said shuttle box front having a spring member adapted to engage the weft yarn and to hold the same against the shuttle at a point between the opening in the shuttle and the shuttle eye to permit 15 the clamping and cutting apparatus to extend through the coinciding openings in the shuttle and shuttle box front to clamp and cut the yarn during a transfer operation.
